UNITED STATES PATENT OFFICE.

MYER DITTENHOEFER, OF NEW YORK, N. Y.

RULER.

SPECIFICATION forming part of Letters Patent No. 331,481, dated December 1, 1885.

Application filed January 2, 1885. Serial No. 151,832. (No model.)

To all whom it may concern:

Be it known that I, MYER DITTENHOEFER, a citizen of the United States, residing at New York, in the county and State of New York, have invented certain new and useful Improvements in Rulers, of which the following is a specification.

My invention relates to certain improvements in rulers for drawing straight and ornamental lines; and the purpose of my invention is to provide a ruler in which, when the ruling-edges are successively brought in position for ruling, a uniform and regular spacing of lines is effected; also, in providing a ruler with elastic ruling-edges, and in other combinations hereinafter more fully set forth.

In the accompanying drawings, which serve to illustrate my invention, Figure 1 is a side view of a ruler containing my improvements. Fig. 2 is a cross-section of the same, and Figs. 3 and 4 are respectively a side and end view of a ruler slightly modified in form.

a represents a ruler, which is preferably made of rubber molded into the required shape. In general form the body is cylindrical, and is provided with the salient angles or projections *b* and re-entering angles *c*, being of a star shape in cross-section. In the present case these are constructed on a triangle, so that the ruler has six radial projections or salient angles, *b*, which extend from end to end of the same. The number of these radial projections may of course vary, and as each of these points forms an edge for guiding the pen, and each in turn is brought into position on the paper, it follows that the greater the number of these projections on the ruler the less will be the spacing between the ruled lines, and vice versa.

Referring to Fig. 2 of the drawings, the ruler *a* has two of its projections *b* resting on the paper *d*. The next upper projection is the ruling-edge for the pen. By then rotating the ruler each projection *b* is successively brought into position over the paper to rule by, and a uniform space is formed between each ruled line. An entire page may be thus lined and spaced with perfect accuracy without removing the ruler from the paper. When a double space is desired between the lines, it is only necessary in rotating the ruler to use every other one of the projections *b* as a guiding-edge for the pen. If a still greater space is required between the lines, every third pro-

jection brought into position by the rotation 55 of the ruler is employed as a ruling-edge. In all cases, however, the lines will be uniformly spaced.

In order to prevent any tendency of the ruler to slip on paper having a peculiarly smooth finish, I tip every other radial projection *b* with soft rubber or equivalent material, as at *e*, sufficiently elastic to produce a slight frictional contact when it is rotated on the paper.

In Figs. 3 and 4 is illustrated a ruler having the same number of radial projections *b*, but with the projections flattened at the edge sufficiently to permit of two ruling-edges on each projection, as seen at *f* and *f'*. Some of these edges *f* may be left straight or smooth, while the opposite edge may be serrated or notched, as seen at *g*, whereby a broken line can be ruled. One of these ruling-edges may have a wavy or undulating outline, *i*, and the other a notched outline, and thus a variety of lines be formed by the use of one ruler.

In the form shown in Fig. 3 the ruler will admit of six ornamental ruling-edges, each of which is capable of producing a different 80 style of line, and six smooth or straight line edges. When ruling by the edge *f*, the pen is held inclining inward, whereas in lining by the edge *i* it is inclined outward. On the side surfaces formed by the projections *b* may be placed lines to indicate different measurements—as a quarter-inch and inch, as at *h*. As there are twelve spaces which may be thus utilized by lines indicating divisions varying in degree, various measurements may be taken 90 or set off by simply turning the ruler so that one or the other side thus marked is brought into position over the paper.

What I claim as new, and desire to secure by Letters Patent, is—

1. As a new article of manufacture, a star-shaped ruler with the points of the star rounded off, as set forth.

2. A ruler star-shaped in cross-section, with the points of the star flattened, as and for the purpose set forth.

3. A star-shaped ruler having the points of the star tipped with soft rubber or other elastic material, as and for the purpose set forth.

MYER DITTENHOEFER.
